UNITED STATES PATENT OFFICE

CLEON V. WILSON, OF SANTA BARBARA, CALIFORNIA

DESIGN FOR A RADIATOR-CAP ORNAMENT

Application filed October 10, 1929. Serial No. 32,988. Term of patent 7 years.

To all whom it may concern:

Be it known that I, CLEON V. WILSON, a citizen of the United States of America, residing at Santa Barbara, in the county of Santa Barbara and State of California, have invented a new, original, and ornamental Design for a Radiator Cap Ornament, of which the following is a specification, reference being had to the accompanying drawing, forming a part hereof.

In the drawing:

Figure 1 is a side elevation of a radiator cap ornament showing my design, and Fig. 2 is a top plan view of the same.

I claim:

The ornamental design for a radiator cap ornament, as shown.

CLEON V. WILSON. [L. S.]
